CONTAINER CONVEYER AND DISTRIBUTOR

Christian N. Bergmann, Pittsburgh, Pa., assignor
of two-sixths to Charles M. Clarke, Sewickley,
Pa.

Application February 16, 1937, Serial No. 126,004

11 Claims. (Cl. 198—32)

My invention is an improvement in distributing conveyers for containers such as bottles, cans, or the like. It is particularly adapted to the art of conveying cylindrical units, as milk bottles, from two sources or stations, to a single station or delivery destination, by merging two rows or columns into one.

Generally stated, it comprises two laterally disposed or side by side feeding conveyers or trackways leading to the receiving terminal or any portion of an intervening delivery conveyer, and controlling means for selectively delivering the approaching terminal unit of the approaching rows or columns and delivering such unit individually and alternately to the single delivery or carry off conveyer.

The active element of the selecting or distributive controlling means consists of a rotatively driven double or single spiral member composed of a pair of right and left hand sections operating alongside the two approaching columns of units to deliver front units thereof alternately to the intervening delivery conveyer, as controlled thereby. The right and left hand sections of the spiral member are so constructed as to locate their terminal flights for such final alternating delivery of oppositely approaching units, in such arrangement.

Alternatively, by utilizing a single conveyer extending between two side-by-side advancing columns of units, it operates to deliver the end-most unit of each column of such pair alternately to the intervening conveyer, running in the same direction.

The present invention is somewhat generally similar in its construction, operation, objects, and functions to that of my Patent No. 2,108,522 for Container conveyer and distributor.

Certain preferred constructions and embodiments of the invention are illustrated in the accompanying drawings, in which:

Fig. 1 is a plan view showing a pair of oppositely approaching feeding conveyers and an intervening delivery conveyer, and co-operating controlling and directing means;

Fig. 2 is a cross section on the line II—II of Fig. 1;

Fig. 3 is a detail view showing a modified construction of a resiliently mounted guard rail;

Fig. 4 is a plan view showing one construction or arrangement for driving the oppositely approaching conveyers of Fig. 1 from the tail shaft of the delivery conveyer;

Fig. 5 is a sectional elevation of Fig. 1 on the line V—V thereof.

I show in Fig. 1 a plan view of one arrangement in which feeding conveyer trackways A and B approach in opposite directions towards the receiving terminal portion of an intervening delivery conveyer C from opposite sides and at substantially right angles thereto. In either case the conveying means of each is conventional and of well known construction, utilizing supporting and conveying belts or chains having base supporting slats or links 2, 3 and 4 respectively.

These are mounted in usual endless chain sections upon head and tail sprockets or the like, with driving and idler shafting, as will be readily understood, and geared for suitable speeds.

Ordinarily, the speed of the delivering or carrying off conveyer C, should be approximately double, or slightly more than double, that of conveyers A and B, enabling it to carry the loads of both with easy and regular distribution. However the relative speeds may be varied or adjusted to the working conditions of the supply sources and receiving terminal to which the individual conveyers may be applied.

Conveyers A and B are defined by the conveyer links or strands 2 and 3 and conveyer C by links or strands 4 in connection with flanking guides 5 and 5a with intervening angle sections 6, along and around which the units a and b pass alternately from conveyers A and B to the single width capacity of conveyer C, for travel of the units thereto. Thus the inner guides 5 merge into the pair of straight guides 5a through the entrance throat to conveyer C thus provided.

Outer guides 5 terminate as shown just beyond the engaging end portions of the co-operating controlling and directing means in the form of spiral members 8, for ensuring alternating delivery of units to conveyer C.

Ordinarily two such converging columns of units will not accurately and continuously merge into a single column without some controlling factor regulating their progress, time, and order of merger without jamming or interference.

In my present improvement I provide for such orderly distribution by replacing otherwise continuous sections of outer guides 5 by the spiral members 8. These are adapted to receive and engage the oncoming units a and b between them and the opposite or inner guides 5, and by their flight engagement, partial retardation, and final delivery, to discharge them alternately onto the conveyer C. As shown, each spiral member 8 is located just above the general supporting level 9 of conveyers A and B, both rotatable in the same direction on their shaft extensions 10, in

2

suitable bearings carried by the general framework. Both spiral members are rotated in the same direction, as indicated by the arrows, by suitable gearing as sprockets 11—12 and chain 5 13, or otherwise, at suitable speeds, from any source of power.

Each such member 8 is provided with a continuous spiral thread or vane 15 and a continuous corresponding intervening spiral groove 16 conforming generally to the curved contour of 10 units *a* and *b* as in Fig. 1. The spiral vane of each is disposed in a direction opposite to the other for regulating and finally imparting opposite and inward feeding movement to the units 15 of both columns, with alternating delivery.

In each member 8 the spiral vane 15 terminates at both ends, and especially at the inner ends, at about 180° or substantially midway of the revolution, of the other, as indicated at 14, and such 20 arrangement contributes materially to their successful operation, in delivering the units alternately to the middle conveyer.

The supporting base portion of the equipment 25 may be of any suitable design approved by good practice, either with or without flooring plates for the chains throughout, except where bridging sections 17 are utilized at the angular junctions between conveyers A, B, and conveyer C. At such points the bridging sections provide smooth 30 surfaces very slightly below the surfaces of the conveyer chain flights and facilitate the passage thereover of the several units.

The tail sprocket 18 of conveyer C is mounted by its shaft 19, and the head sprockets 20 of conveyers A and B by their shafts 21, in a suitable frame 22, as in Figs. 4 and 5.

Shaft 19 is operatively connected with shafts 21 by suitable gearing, as bevels 23, 24, properly proportioned to transmit motion to conveyers A and B from conveyer C at desired relative speeds. 40 Under normal conditions, with approaching loads on conveyers A and B equalling the receiving capacity of conveyer C, the speed of travel of conveyer C should be approximately twice that of conveyers A and B, as indicated by the one to two pitch diameter ratio of gears 23, 24.

However, under other conditions, as because of delayed supply, or irregularly spaced apart continuity of units on conveyers A and B, they may be 50 operated at a relatively faster speed by modifying the gear ratio, dependent on operating conditions.

In the construction shown the conveyer flights 2, 3 and 4 are maintained in their desired horizontal travel by supporting flanges 25.

I show in Fig. 3 a modification of the inner guide bar equipment in which a separate extension 55 5b is resiliently mounted as by springs 26 and studs 27 engaging resisting and limiting abutments 28. Such mounting provides against undue strains or breakage of the units due to possible jamming or congestion, as in case of an upset bottle, in passage of the units between spiral member 8 and the guide rail.

In operation, assuming two advancing columns 65 of units *a* and *b*, the front one of either, in passing beyond the oppositely spaced guide bars 5, will be engaged by the confronting edge of the adjacent terminal 14 of spiral vane 15. Thereafter, as the column advances, each next adjacent unit is successively engaged and maintained centrally in its path, bearing with slight clearance against the concave spiral face 16 at one side and against the guide bar 5 at the other side of 75 conveyer A and B, or of either.

Ordinarily such engagement by spiral member 8 tends to slightly retard the inward travel of the engaged units, until the foremost one thereof passes from the underrunning flights 2 and 3, or either, onto the stationary bridge 17. At such time the inner end portion of vane 15 by its opposite edge itself becomes the moving element and forcibly ejects the unit across the bridge, assisted by pushing action of the next adjacent oncoming unit, as in the case of small diameter units, onto the carry-off conveyer C.

The spiral member 8 thus acts as a control means for the feed of units to the middle or carry-off conveyer C, by alternately delivering a single unit thereto, one from each side.

It acts to regulate the delivery at any desired speed, and the speed of rotation of spiral members 8 is independent of the speed of conveyers A and B.

By the above described construction, the feeding conveyers approach the carry-off conveyer from opposite sides, as in Fig. 1 and with double side control of either or both approaching column or columns, with resulting regular selection and delivery control of individual units passing to the faster moving conveyer C.

The operation as to carrying the load or loads of either or both supply conveyers by an intervening faster speed delivery conveyer, is successfully effected in function and results.

The shifting of each unit at the junction onto the common delivery conveyer is easily and regularly effected by the relatively slow and fast speeds, controlled and assisted by the co-operating spiral members 8; by the open throat of the receiving conveyer; the lateral guide bars ensuring continuous contact with the conveyer flights, and the propelling action on the units of the terminal vane of either spiral member in assisting their movement over the bridge.

I claim:

1. In combination, a delivery conveyer, a pair of relatively slower feeding conveyers leading thereto, and rotatable unit-movement-controlling spiral conveyers each located adjacent to the junction of said conveyers and each in operative relation to one of the feeding conveyers.

2. In combination, a delivery conveyer, a pair of relatively slower feeding conveyers leading thereto, a pair of rotatable unit-movement-controlling spiral conveyers located adjacent to the junction of said conveyers and in operative relation to the feeding conveyers, and means effecting simultaneous rotation of said spiral conveyers.

3. In combination, a delivery conveyer, a pair of relatively slower feeding conveyers leading thereto, guides for said feeding conveyers directing units from the feeding conveyers towards the delivery conveyer, guides for the delivery conveyer having diverging connection with adjacent feeding conveyer guides, a pair of rotatable unit-movement-controlling spiral conveyers located adjacent to the junction of the said conveyers and in operative relation to the feeding conveyers, and means effecting rotation of said spiral conveyers.

4. In combination, a pair of feeding conveyers, a delivery conveyer of faster speed, unit directing guides flanking said conveyers having junction connection between the feeding conveyers and the delivery conveyer providing a converging throat for the delivery conveyer, a pair of rotatable unit-movement-controlling spiral conveyers located adjacent to the junction of said conveyers.

and in operative relation to the feeding conveyers, and means effecting rotation of said spiral conveyers.

5. In combination, a delivery conveyer of sufficient speed and capacity to receive and transfer the discharge thereto of contributing conveyers, a pair of contributing conveyers leading thereto at opposite sides, unit supporting bridge members between the contributing conveyers and the 10 delivery conveyer, a pair of rotatable unit-movement-controlling spiral conveyers located adjacent to the junction of said conveyers and in operative relation to the contributing conveyers, and gearing connected with the spiral conveyers, 15 for simultaneous operation for engagement of a conveyed unit of a contributing conveyer.

6. In combination, a delivery conveyer of sufficient speed and capacity to receive and transfer the discharge thereto of contributing conveyers, a pair of contributing conveyers leading thereto at opposite sides, unit supporting bridge members between the contributing conveyers and the delivery conveyer, flanking guide members for said conveyers disposed at their junction for reception of laterally directed conveyed units from the contributing conveyers to the delivery conveyer, a pair of rotatable unit-movement-controlling spiral conveyers located adjacent to the junction of said conveyers and in operative relation to the contributing conveyers, and gearing connected with the spiral conveyers for simultaneous operation for engagement of a conveyed unit of a contributing conveyer.

7. In combination, a single line delivery conveyer of sufficient speed and capacity to receive and transfer the double line discharge thereto of contributing conveyers, a pair of contributing conveyers leading thereto from opposite sides, a pair of rotatable unit-movement-controlling spiral conveyers located adjacent to the junction of said conveyers and in operative relation to the contributing conveyers, and gearing engaging the spiral conveyers for simultaneous operation when in engagement with a conveyed unit of a contributing conveyer.

8. In combination with two independent conveyers adapted to deliver cylindrical units alternately to an intervening carry-off conveyer, guides therefor, a pair of rotatable unit-movement-controlling spiral conveyers each having equally spaced concave faces approximating unit contour curvature between adjacent spiral vanes traversible partway across said two conveyers into the paths of articles carried thereby for engagement of an advancing unit at either side of

the carry off conveyer, and means effecting rotation of said spiral conveyers.

9. A container conveyer and distributor for bottles or the like comprising a pair of side conveyers adapted to receive the bottles and upon which they travel in single rows, a single intervening delivery conveyer operating at a faster speed than said pair, guides for said conveyers including deflected sections at the junction between the pair and said single conveyer, a pair of 10 rotatable unit-movement-controlling a spiral conveyers each located in the path of bottles being moved along the pair of conveyers, the spiral edges of said conveyers being arranged for individual alternating engagement by and between the adjacent units of each row thereof, and means connected with said spiral conveyers causing them to operate in unison and distribute the bottles alternately and automatically into a single row travelling on the delivery conveyer.

10. A container conveyer and distributor for bottles or the like comprising a pair of side conveyers adapted to receive the bottles and upon which they travel in single rows, a single intervening delivery conveyer operating at a faster 20 speed than said pair, supporting flooring bridge portions over which the bottles pass at the connecting junction between the pair and single conveyer, guides for said conveyers including deflected sections at the junction between the pair and single conveyer, a pair of rotatable unit-movement-controlling spiral conveyers each located in the path of bottles being moved along the path of the side conveyers, the spiral edges of said spiral conveyers being arranged for individual alternating engagement by and between the adjacent units of each row thereof, and means connected with said spiral conveyers causing them to operate in unison and distribute the bottles alternately and automatically into a single 25 row travelling on the delivery conveyer.

11. In combination, a pair of feeding conveyers arranged at opposite sides of an intervening delivery conveyer, said delivery conveyer having its receiving end portion extending between and beyond the delivery end portions of said feeding conveyers, a pair of rotatable unit-movement-controlling spiral conveyers each mounted at one side of one feeding conveyer and having spiral edges extending partway across the path of said feeding conveyers for engagement of units moved thereby, and cooperating guides providing for reception on and by the delivery conveyer of units delivered from the feeding conveyers.

CHRISTIAN N. BERGMANN.
